By Atty.
Detwill C. Allen,

UNITED STATES PATENT OFFICE.

HARRISON OGBORN, OF RICHMOND, ASSIGNOR OF ONE-HALF OF HIS RIGHT
TO SAMUEL WATSON, OF DUBLIN, INDIANA.

WASHING-MACHINE.

SPECIFICATION forming part of Letters Patent No. 230,714, dated August 3, 1880.

Application filed June 24, 1880. (No model.)

To all whom it may concern:

Be it known that I, HARRISON OGBORN, a citizen of the United States, residing at Richmond, in the county of Wayne and State of Indiana, have invented certain new and useful Improvements in Boiler Washing-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

15 Figure 1 represents a longitudinal vertical section of my improved boiler; Fig. 2, a transverse vertical section of the same.

20 My invention relates to certain new and useful improvements in boiler washing-machines, having for its object the subjection of the clothes to be washed to fine streams of water or other fluids while the same are being held up out of the water in a steam-bath; and to this end the invention consists in the novel construction and combination of parts, all as will be hereinafter fully described, and specifically pointed out in the claims.

25 To enable others skilled in the art to make and use my invention, I will now proceed to 30 describe its construction and mode of operation.

In the drawings, A represents a vessel of 35 rectangular shape, and in construction similar to the ordinary stove wash-boiler, and B a slotted or perforated cylinder suspended in bearings *a a*, and so that its lower side will always be above the water-line in the boiler, as clearly shown by dotted lines, Fig. 2. One of the journals, *b*, of said cylinder is made hole 40 low for the reception of one end of a crank, C, which passes through an opening in one end of the boiler, for the purpose of revolving said cylinder.

D represents the cover of the boiler, provided on its under side with a broad and thin flat reservoir, E, having on its under side a long perforated trough or receptacle, F. The lid or cover D is provided with a funnel, *d*, in its top, for the introduction of the water or other

washing-fluids, and which can be closed by a cork or other suitable device.

e represents a hole or opening through the bottom of the reservoir E, for the passage of the water or other fluids to the trough or receptacle, which has a series of perforations 55 through one or both sides thereof, for producing a fine stream, that falls down onto the clothes placed in the cylinder or receptacle B. The opening *e* is controlled by a stop-valve, *e'*, which is raised and lowered or adjusted vertically by a thumb-screw, *d''*, that screws onto the upper end of the valve-stem *d'*, passing up through the reservoir and top of the cover.

The cylinder is provided with a hinged cover, *b'*, for the purpose of placing the clothes to be 60 washed therein, and the vessel is provided at one end and near the bottom with a stop-cock, *a'*, for drawing off the water, so that it will never get above the water-line.

The operation of my improved apparatus is 70 as follows: The clothes to be cleaned, being previously soaked in warm water and soap rubbed into the parts most soiled, are placed into the cylinder B. A small quantity of water is then put into the vessel A, but not enough 75 to reach up to the cylinder. The cover D is then placed on the vessel, and the reservoir E filled with clean soapsuds or water, and the opening or outlet through the bottom thereof closed by the valve *e'*, through the medium of the 80 thumb-screw *d*. The boiler is now placed on the stove over the fire, and as soon as the boiler is full of steam the valve *e'* is adjusted by the thumb-screw, so as to allow the hot water in the reservoir, which has been heated by the steam 85 and heat in the boiler, to flow into the perforated trough on the under side of the reservoir, and thence down in a fine stream upon and through the clothes, the cylinder being turned every few minutes in order to change the position of the clothes; and after a short time 90 the clothes are taken out, and they will present the same condition as if they had been through the ordinary mode of washing in two waters and subsequently boiled.

Having thus fully described my invention, what I claim as new, and desire to secure by Letters Patent, is—

1. The combination, with the vessel A, of an interior receptacle for holding the clothes above the water, an interior reservoir arranged above said receptacle for containing clean water or other washing-fluids, and a perforated trough arranged under said reservoir and above the clothes-receptacle, whereby the clothes are subjected to a steam bath out of the water in said vessel, and the clean water or other washing-fluids in said reservoir heated and permitted to drop in a fine stream upon and through the clothes, substantially in the manner herein shown and described.
2. The combination, with the vessel A, of an interior slotted revolving cylinder, B, cover D, provided with reservoir E, and the perforated trough or receptacle F, arranged under said reservoir, substantially as and for the purpose specified.
3. The combination, with the vessel A, having an interior receptacle for holding the clothes above the water, of a cover, D, provided with a reservoir, E, on its under side,

fitting inside of said vessel, having a hole or opening through its bottom, an adjustable valve, e', for controlling said opening, and a perforated trough or receptacle, F, connected to the under side thereof, substantially as and for the purpose herein shown and described.

4. The herein-described boiler washing-machine, consisting of vessel A, having stop-cock a', interior revolving cylinder, B, arranged above the water-line of said vessel, cover D, having a reservoir on its under side provided with opening e, valve and valve-stem e' d', 35 thumb-screw d, and perforated trough or receptacle F, connected to and arranged under said reservoir, substantially as and for the purpose specified.

In testimony whereof I affix my signature 40 in presence of two witnesses.

HARRISON OGBORN.
